UNITED STATES PATENT OFFICE.

CAROLYN M. LIGHT, OF LOS ANGELES, CALIFORNIA, AND LOUISA ARCHER, OF ROCHESTER, NEW YORK.

SIFTER.

Application filed December 3, 1923. Serial No. 678,156.

To all whom it may concern:

Be it known that CAROLYN M. LIGHT and LOUISA ARCHER, both citizens of the United States, and residing, respectively, at Los Angeles, California, and Rochester, New York, have invented certain new and useful Improvements in Sifters, of which the following is a specification:

This invention relates generally to sifters, and particularly to sifters for household or domestic use, the primary object of the invention being to provide a sifter which shall be of simple construction and therefore of inexpensive manufacture, and yet which will 15 prove thoroughly practical and efficient in use.

A further object of the invention is to provide a sifter of such construction and which operates in such manner that material 20 passing through the sifter will be screened a number of times at one and the same operation.

A further object is to provide a sifter of that type wherein a plurality of screens are 25 employed, characterized by a novel construction and assemblage of the casing and screens, as well as the agitator, which enables the device to be easily assembled with simple operations, which minimizes the opportunity for wear, breakage or dismemberment of the parts, which may be easily 30 operated, which quickly performs its screening operations, which may be quickly and easily relieved of foreign matter, such as 35 dirt, grit, etc., and which will prove thoroughly capable of carrying forth its several operations.

With these objects in view, together with others which will appear as the description 40 proceeds, the invention consists in the novel construction, assemblage and arrangement of parts, all as will be described more fully hereinafter, illustrated in the drawings, and particularly pointed out in the claims.

45 In the drawings;

Fig. 1 is a vertical sectional view taken through a sifter constructed in accordance with the invention, and

50 Fig. 2 is a top plan view of the improved sifter.

Referring now more particularly to the drawings, the body or barrel of the improved sifter is indicated generally at 3, and is preferably formed of thin inexpensive 55 sheet metal shaped into cylindrical form.

This barrel, which may be of any suitable height and diameter, is provided at one side with a handle or grip 4 of conventional construction; the ends of which are extended into suitable openings near the upper and 60 lower ends of the cylinder, and secured therein as shown.

The interior of the barrel is divided into three chambers 5, 6 and 7, and these chambers are formed by arranging within the 65 barrel the screens 8, 9 and 10. These screens are formed of the usual sifter screen fabric or wire, and may be of the same size mesh, or the meshes of the several screens may be different, as desired. The screens 70 are arranged parallel to each other and are securely held properly positioned within the barrel. The upper screen 8 and the next underlying or intermediate screen 9 are held in place in the same manner. Each of these 75 screens, circular in form as will be understood, is of slightly larger diameter than the interior of the barrel, and rest at their edges upon the inwardly projecting annular ribs 11 formed in the wall of the barrel at 80 the proper places. The extreme edge portions of these screens are turned up as shown, and are engaged by the expandable or spring rings 12; the latter exerting pressure upon the up-turned portions of the 85 screens and tightly forcing the same into engagement with the inner walls of the barrel and with the upper surfaces of the ribs 11.

The lower screen 10 is constructed similar to those above described, excepting that the extreme edge is turned down and is to be received within the pocket or recess formed by crimping the lower edge of the barrel. This crimped portion, indicated at 95 13, tightly binds the lower screen in place and maintains the same in its proper position at all times.

Each of the screens 8, 9 and 10 is provided centrally with an opening for the reception of the shaft of the agitator, and each of these openings may be provided with a ring to prevent fraying of the fabric and to provide a suitable bearing for the said shaft. These rings are indicated at 14, and may be 100 secured to the fabric in any suitable or approved manner.

The agitator has its lower end protruding through the ring in the lower end of the barrel and through a washer 15, and is en- 110

larged or flattened at its lower extremity whereby the shaft is locked in position against any upward movement. That portion of the shaft immediately above the screen 10 is deflected laterally as at 16 and is then rebent as at 17 to provide an agitator portion of such length as to substantially reach from side to side of the barrel and to be capable of sweeping the entire upper surface of the lower screen 10. The shank or shaft then extends through the ring of the intermediate screen 9 and is bent laterally as at 18 to provide an agitator for the said screen. This agitator is disposed in a direction diametrically opposite to the member 16—17, and is of substantially the same length as the latter agitator. The agitator arm 18 is then rebent upon itself as shown, and passes upwardly through the ring in the screen 8, whereupon it is bent so as to provide a double agitator arm 19 capable of sweeping the upper surface of the top screen 8. From the extremity of this arm portion, the shank extends to the axis of the barrel and is continued upwardly and then deflected to form a crank arm 20, to the end of which is attached a knob 21, for obvious purposes. The upper part of the shank or shaft is steadied in a bearing formed in the central part of the cross brace 22. In this manner the shaft is securely held in position in the barrel and cannot remove itself therefrom, because of the locking arrangement at the under side of the lower screen, and because of the manner in which the several sweeper arms prevent the shaft moving downwardly in the barrel.

Each of the chambers 6 and 7 is provided with means whereby the same may be relieved of any foreign matter which may collect therein or be gleaned from the material being sifted. The side wall of the barrel adjacent to each of these chambers is provided with an opening 23, closed by a plate or gate 24. These openings are normally closed but may be quickly opened when required by merely turning the doors upon their pivot connections 25, as will be understood.

In operation, the flour or other material to be sifted or screened is poured into the upper end of the barrel and the agitator is turned. This causes the material to be worked and agitated, and in the course of this operation the finer materials pass through to the next underlying screen. The same operation, of course, is being carried out on this latter screen; the heavier particles being retained thereby while the finer materials pass to the bottom screen. The material passing through the bottom screen is thoroughly freed of grit or other foreign matter and a high degree of fineness is assured. Any large particles trapped in the compartments 6 and 7 may be removed

therefrom by simply opening the doors 24 and tilting the sifter slightly, while foreign matter that may have collected above the upper screen 8 may be removed therefrom in an obvious manner.

70

With a sifter constructed in accordance herewith, it is at once apparent that the materials operated upon are, at a single operation, given three different screenings, and separate operations to the accomplishment of the same end are obviated. By constructing the screens, barrel and agitator in the manner set forth it is obvious that simplicity in manufacture and consequent cheapness of sale are assured without detracting from the high degree of efficiency the article attains.

75

80

While the above is a description of the invention in its preferred embodiment, it is apparent that changes in the details of construction of the several parts and the assemblage of the same may be resorted to without departing from the spirit of the invention as defined by the claims.

85

Having thus described our invention, we claim:

90

1. In a sifter, a barrel, a plurality of screens arranged in spaced parallel relation in said barrel and each having a central opening, a shaft rotatably supported in said openings, the said shaft being bent upon itself above each screen to provide a pair of spaced upper and lower arms extending radially of the screens, the upper arm of each pair being disposed a substantial distance below the screen above the same to break up particles of material forced through said screen and to aerate said material, and the lower arms lying close to their respective screens to form sweeps therefor to force material through said screens.

95

2. In a sifter, a barrel, a plurality of screens arranged in spaced parallel relation in said barrel and each having a central opening, a shaft rotatably supported in said openings, the said shaft being bent upon itself above each screen to provide a pair of spaced upper and lower arms extending radially of the screens, the upper arm of each pair being disposed a substantial distance below the screen above the same to break up particles of material forced through said screen and to aerate said material, the said upper arms being disposed in nearer proximity to the lower screens than to the nearest adjacent upper screens, and the lower arms lying close to their respective screens to form sweeps therefor to force material through said screens.
